Primary Examiner — Susan Bennett Hattan*Assistant Examiner* — Brett Miller*(74) Attorney, Agent, or Firm* — Polsinelli PC(57) CLAIM

I claim the ornamental design for an outdoor grill, as shown and described.

DESCRIPTION

FIG. 1 is a perspective view of an outdoor grill, showing my new design;

FIG. 2 is a front elevational view thereof;

FIG. 3 is a left side elevational view thereof;

FIG. 4 is a rear elevational view thereof;

FIG. 5 is a right side elevational view thereof;

FIG. 6 is a top plan view thereof; and,

FIG. 7 is a bottom plan view thereof.

Broken lines are for illustrating unclaimed portions of the outdoor grill; the broken lines form no part of the claimed design.
